UNITED STATES PATENT OFFICE.

ROY H. ADAMS, OF BOYNTON, OKLAHOMA.

MECHANISM FOR MOVING ENGINES OFF OF DEAD-CENTERS.

1,335,086.

Specification of Letters Patent. Patented Mar. 30, 1920.

Application filed July 8, 1919. Serial No. 309,273.

To all whom it may concern:

Be it known that I, Roy H. Adams, a citizen of the United States, residing at Boynton, in the county of Muskogee, State 5 of Oklahoma, have invented certain new and useful Improvements in Mechanism for Moving Engines Off of Dead-Centers; and I do hereby declare the following to be a full, clear, and exact description of the invention, such as will enable others skilled in the art to which it appertains to make and use the same.

This invention relates to attachments for steam engines such as are commonly employed in connection with oil derricks although it will be understood from the following description that it may be employed in connection with an explosive engine and it is the object of the invention to provide 15 a simple means that may be associated with the engine for shifting the crank shaft in either direction from a dead center and which apparatus may furthermore be operated from a convenient distance.

20 In the drawings:

Figure 1 is a plan view including a conventional illustration of an engine equipped with a mechanism embodying the present invention.

25 Fig. 2 is a side elevation of the structure shown in Fig. 1 and showing the kicker mechanism inactive.

Fig. 3 is a vertical section on line 3—3 of Fig. 2 looking to the left and showing the 30 position of one of the kicking segments beneath the fly wheel.

Fig. 4 is a detailed sectional view on line 4—4 of Fig. 2 to show the manner of attaching the rack segments to the fly wheel.

40 Referring now to the drawings there is represented a steam engine comprising a base 5 upon which is the cylinder 6 and the pillow blocks 7, in which latter is journaled the usual crank shaft 8 with which the piston rod 9 is connected in the usual manner. There is of course also provided a cut-off mechanism and such other attributes as go 45 to constitute the steam engine commonly employed in connection with an oil derrick, and these form no part of the present invention.

Under working conditions, the engine at 50 times stops at a dead center when frequently it is vital that it be in motion. Under such conditions, it is customary for the engineer to throw it off of the dead

center in any of a variety of inconvenient ways and it is to overcome such inconveniences that the present invention is provided.

60

The present kicking mechanism includes the provision of segmental racks 10 to the periphery of the fly wheel 11 of the engine in spaced relation, together with means to engage these racks interchangeably and 65 move them with the fly wheel, in corresponding opposite directions.

Each rack 10 is formed upon the convexed face of a channeled shoe that embraces a portion of the periphery and the 70 side edges of the fly wheel, the shoe having stud bolts that are engaged through a curved clamping plate 12 on the inner periphery of the fly wheel, beyond which they are provided with clamping nuts 13.

75

Beneath the fly wheel 11 is disposed the base 14 of an additional member of the present equipment and from each end of which rise a pair of pillow blocks 15 having journaled therein the rock shaft 16 each 80 provided at one end with a crank 17, it being noted that the cranks while parallel, extend oppositely from their respective shafts.

Fixed upon each shaft 16 between the corresponding pillow blocks 15 is a seg- 85 mental gear 18 so arranged and proportioned that when its shaft is rocked, it will engage the corresponding rack 10, when the engine is on a dead center and after moving the fly wheel with the shaft an angular distance sufficient to carry the engine off the dead center, will then return to its original position, illustrated in Fig. 2.

The segmental gears 18 are held normally in their retracted positions by means of the 95 helical springs 19 each of which is connected at one end to the gear, as illustrated while the other end is connected to the upwardly directed brackets 19 carried by the base 14 and having a cage 20 within which the 100 spring is confined, the cage serving also as a stop to limit the return movement of the segmental gear and its rock shaft.

To actively move each segmental gear 8, as distinguished from the passive movement contributed by its spring 18, there is connected to the corresponding crank 17, a cable 21, preferably of wire which is connected at its opposite end to one end of a foot lever or pedal 22. The two pedals 22 for the two 110 cables 21, are mounted upon a single rock shaft 23 carried in pillow blocks 24 upon a

- base 25 which in practice is positioned convenient to the throttle 26 of the engine so that without leaving the throttle, the engineer may actuate either foot lever or pedal 5 to pull the corresponding cable 21 and through the medium of the connected lever 17 and segmental gear 8, shift the fly wheel in either direction for corresponding subsequent rotation of the crank shaft.
- 10 It will of course be understood that the bases 14 and 25 may be secured upon any suitable foundation, such as the convenient timbers.
- 15 What is claimed is:—
1. The combination with an engine and a rotatable part thereof, of a rack carried by such rotatable part, an oscillatory gear mounted and formed to engage the rack when the engine is on dead center and under 20 influence of movement of which gear the rack and therewith the movable part of the engine is shiftable past the dead center, and from which engagement the gear is movable, means for moving the gear actively 25 with respect to the rack, and means for returning and holding the gear yieldably in inactive position.
2. The combination with an engine and its fly wheel, of a pair of spaced shoes 30 movably connected thereto and each provided with rack teeth disposed transversely of the periphery of the fly wheel, segmental gears for the racks mounted to engage their racks move the fly wheel angular distances 35 in opposite directions, means for engaging

the gears interchangeably with their racks and moving them in such engagement to subsequent disengagement and separate means for returning and holding each gear in inactive position.

40

3. The combination with an engine and its fly wheel having peripheral rack teeth, of a pair of gears engageable and disengageable with respect to certain of the rack teeth upon continuous movement in one direction, 45 means for thus moving each gear and separate means for returning each gear for disengagement and for holding it yieldably in returned position.

45

4. The combination with an engine and 50 its fly wheel having spaced series of removable transverse peripheral rack teeth, of a segmental rack gear for each series of rack teeth, disposed to interchangeably engage and move the rack teeth with the fly 55 wheel upon movement of the gears in opposite directions, a pair of pedals each connected with a gear for actuating it, a spring connected with each gear and adapted to return and hold it yieldably in inactive position and a cage for each spring disposed to limit the return movement of the corresponding gear.

55

In testimony whereof, I affix my signature in the presence of two witnesses.

ROY H. ADAMS.

Witnesses:

LEONA CARROWS,
J. F. WOLFINGER.
